(57) CLAIM

The ornamental design of the box for a telephone handset, as shown and described.

DESCRIPTION

FIG. 1 is a front view of the box with a telephone line,
handset recess, and handset shown by dotted lines;

FIG. 2 is a top view of the box with a telephone line,
handset recess, and handset shown by dotted lines;

FIG. 3 is a one side view of the box;

FIG. 4 is a rear view of the box with a telephone line shown by dotted lines;

FIG. 5 is the other side view of the box; and,

FIG. 6 is a bottom view of the box with a telephone line

The broken line shown throughout the views are for illustrative purposes only and form no part of the claimed design.
